CLAIM

The ornamental design for a cookware vessel, as shown and described.

DESCRIPTION

FIG. 1 is a top perspective view of a cookware vessel according to the new design;

FIG. 2 is a bottom perspective view of the outer surface of a cookware vessel shown in FIG. 1;

FIG. 3 is a top view of the cookware vessel shown in FIG. 1; FIG. 4 is a bottom view of the cookware vessel shown in FIG. 1;

FIG. 5 is a side elevation view of the cookware vessel shown in FIG. 1;

FIG. 6 is an opposite side elevation view of the cookware vessel shown in FIG. 1;

FIG. 7 is a left end view of the cookware vessel shown in FIG. 1;

FIG. 8 is a right end view of the cookware vessel shown in FIG. 1;

FIG. 9 is a cross-sectional view taken along the line 9-9 of the cookware vessel shown in FIG. 5;

FIG. 10 is a cross-sectional view taken along the line 10-10 of the cookware vessel shown in FIG. 3;

FIG. 11 is a cross-sectional view taken along the line 11-11 of the cookware vessel shown in FIG. 5;

FIG. 12 is a cross-sectional view taken along the line 12-12 of the outer surface of a cookware vessel shown in FIG. 6;

FIG. 13 is a top perspective view of another embodiment of a cookware vessel according to the new design;

FIG. 14 is a bottom perspective view of the outer surface of a cookware vessel shown in FIG. 13;

FIG. 15 is a top view of the cookware vessel shown in FIG. 13;

FIG. 16 is a bottom view of the cookware vessel shown in FIG. 13;

FIG. 17 is a side elevation view of the cookware vessel shown in FIG. 13;

FIG. 18 is an opposite side elevation view of the cookware vessel shown in FIG. 13;

FIG. 19 is a left end view of the cookware vessel shown in FIG. 13;

FIG. 20 is a right end view of the cookware vessel shown in FIG. 13;

FIG. 21 is a cross-sectional view taken along the line 21-21 of the cookware vessel shown in FIG. 17;

FIG. 22 is a cross-sectional view taken along the line 22-22 of the cookware vessel shown in FIG. 15;

FIG. 23 is a cross-sectional view taken along the line 23-23 of the cookware vessel shown in FIG. 17; and,

FIG. 24 is a cross-sectional view taken along the line 24-24 of the outer surface of a cookware vessel shown in FIG. 17.

In the drawings, the broken lines form no part of the claimed design.
